CLAIM

The ornamental design for a chandelier, as shown and described.

DESCRIPTION

FIG. 1 is a perspective view of a chandelier, showing my new design;

FIG. 2 is a front elevation view thereof;

FIG. 3 is a rear elevation view thereof;

FIG. 4 is a left side elevation view thereof shown on an enlarged scale for clarity of disclosure;

FIG. 5 is a right side elevation view thereof shown on an enlarged scale for clarity of disclosure;

FIG. 6 is a top plan view thereof; and,

FIG. 7 is a bottom plan view thereof.

In the drawings, the broken lines illustrate portions of the article which form no part of the claimed design.

1 Claim, 7 Drawing Sheets(56)
